UNITED STATES PATENT OFFICE.

EDWARD THOMAS HANNAM, OF CINCINNATI, OHIO.

WATER-TUBE BOILER.

SPECIFICATION forming part of Letters Patent No. 761,829, dated June 7, 1904.

Application filed November 27, 1903. Serial No. 182,861. (No model.)

To all whom it may concern:

Be it known that I, EDWARD THOMAS HANNAM, a citizen of the United States, residing at Cincinnati, county of Hamilton, and State 5 of Ohio, have invented certain new and useful Improvements in Water-Tube Boilers, of which the following is a full, clear, and exact description, reference being had to the accompanying drawings, forming part of this specification.

It is usual in water-tube-boiler construction to provide a steam drum or drums above and parallel to the series of water-tubes and to rivet the water-legs at front and rear to the steam-drum. This riveting necessarily has to be done by hand or by hand-machine, a matter of considerable expense in construction, and in addition material is wasted in cutting the water-leg plates to fit, and the plates have to 15 be heated and shaped in various ways to conform to the surface of the drum. In older constructions the water-leg throats are necessarily constricted, which tends to impede the circulation, which necessitates as much depth 20 as possible of each water-leg, and consequently longer stay-bolts to hold the water-leg plates together than would be required were the delivery from the water-legs free and open throughout. In addition to this in expanding the water-tubes into the water-legs a longer 25 mandrel has to be employed, and the expense and difficulty of operation is necessarily increased where there is considerable space between the front and the rear plate of the water-leg. In such older constructions the boiler 30 cannot be shipped in sections, and great expense is frequently incurred in installing such boilers by reason of their cumbersome dimensions. Where ordinary steam-drums are employed in connection with the water-tubes 35 and in order to furnish superheated steam, superheating appliances have to be added at considerable additional expense, as the steam-drums alone obviously cannot be used for superheating purposes.

My invention is directed toward overcoming these difficulties; and its object is to provide a safe, durable, and economical water-tube boiler which may be shipped in sections 40 when required, which can be riveted by ma-

chine without hand-driven rivets, in which no flanging or fitting of the water-legs to the steam-drum is required and no waste of material incurred, in which there are no seams exposed to the fire or hot gases, in which superheated steam is always furnished without additional superheating appliances, and which in many other ways to be hereinafter referred to is very economical in construction, occupies less space with the same length of 55 tube-surface, and which can be used for marine construction as well as on land.

In the drawings, Figure 1 is a sectional side elevation of my improved water-tube-boiler construction. Fig. 2 is a cross-sectional elevation of same. Fig. 3 is a vertical section of a modified construction of water-leg and drum. Fig. 4 is a plan view of a portion of the water-leg drum, showing method of bracing the throat of the water-leg.

The boiler is provided with the usual heating appliances, in which A is the base, and B is the front wall; C, the rear wall; D, the grates; E, the ash-pit; F, the bridge wall, and G the combustion-chamber.

H represents the series of water-tubes running lengthwise of the furnace arranged in the usual staggered series and provided with the front and rear water-legs L M, into which the water-tubes are expanded in the usual way. The outer plates of the water-legs are provided with the usual hand-holes for access to the water-tubes, the hand-holes being closed by hand-hole plates with gaskets and the usual crabs and bolts a a.

N P are water-leg steam-drums, which are a part of the water-leg construction and which run parallel to and opening into the leg portion throughout its entire width.

In the usual construction of water-tube boilers it is customary, as heretofore noted, to provide one or more steam-drums parallel with the water-tubes and to which the front and rear water-legs are riveted, with necessarily narrow and constricted openings from 90 the water-legs into the steam-drums. My construction is a complete departure from this older arrangement. My steam-drums are a part of the water-legs and can be called very properly "water-leg" drums. These steam-

drums and water-leg portions are preferably made of suitable wrought-steel plates—a front plate, and a rear plate. The upper portions of these plates *b c* are rolled in a cylindrical shape, the lower portions *d e* being flat and in which flat portions are punched the holes for the water-tubes and the hand-hole openings, and the two plates making up the steam-drum and water-leg are then riveted together 5 at the top at *f* and at the bottom at *g*. Instead of this construction the water-leg drum can be rolled in a single cylinder and the water-leg riveted thereto, as shown in Fig. 3. In either case, however, it is necessary to 10 properly brace the construction at the opening between the water-leg and the drum. In order not to obstruct this passage-way, I provide the necessary number of brace-plates *mm* of sufficient width and thickness and twist 15 these brace or stay plates, so that the flat ends *ll* may be riveted to the drum on each side and the twisted edge of the plates will extend across the opening. In this way without obstructing the opening I obtain ample strength 20 and rigidity of construction. The heads for the drums and water-legs are then riveted in place, and the water-leg and drum construction is complete. 25

It will be noticed that the water-leg being a 30 part of the drum construction there is no waste of material nor shaping and fitting of the water-leg to the steam-drum, and, moreover, that there is no seam in any way exposed to the hot gases. Inasmuch as the water-legs 35 open throughout their entire length into the drums, these openings are in no way constricted, so that I am able to provide less depth for the water-legs, and therefore shorter stay-bolts can be used, giving greater rigidity 40 and durability at less expense.

The rear water-leg drum can be of considerably larger diameter than the front drum, as it is into this drum that the feed-water is delivered. In this drum I arrange a mud-pan 45 or purifier, and it is evident that a much larger purifier can be employed than in the ordinary constructions, as the mud-pan can extend nearly the entire length of the drum.

To provide for the water circulation between 50 the drums *N P*, I arrange in the length of the drums a series of equalizer-pipes *S*, the lower set below and the upper set above the usual water-line of the drums, and, as usual, to insure proper circulation, the water-tubes *H* of 55 the boiler are inclined to the rear. Located intermediate the end drums, parallel thereto and somewhat higher, is a steam-drum *T* with the steam-outlet *U*, and the drum is connected with each water-leg drum above the water-line by the tubes *V*, which can be of a number of rows to get a greater superheat in the steam. 60

Above the steam-tubes *V* the tile-roof *W* of the boiler is constructed. Flue-partitions can be arranged to direct the course of the fire 65 and hot gases in any desired way; but I pre-

fer to provide two horizontal partitions *Y Y*, one at the bottom and one at the top of the water-tubes *H*, so as to direct the course of the fire from the combustion-chamber *G* at the rear to the front water-leg at the top, so as to obtain the full effect of the fire throughout the length of the water-tubes. The course of the fire and hot gases is then around the equalizer-tubes *S* and the steam-tubes *V* and out through the smoke-outlet *Z*. It is evident 70 that the equalizer-tubes will furnish a much more economical exposed surface to the fire than the usual steam drum or drums and that the steam-tubes *V V* will become superheater-tubes, so that only superheated steam will be 75 carried to the steam-drum *T*, which drum also has considerable heating-surface.

By means of the construction in which the water-drums are located across the ends of the boiler-tubes at right angles thereto with the 80 steam-drum above the plane of the water-leg drums it is evident that my construction of boiler can be used in marine propulsion, as the rolling and tossing of the vessel will not be sufficient to throw any water into the intermediate steam-drum, which can be placed, as will be readily understood, at any desired height. As will be seen, practically all of the 85 heating-surface of the boiler is a tubular surface, so that circulation is positive, steam 90 conversion very effective, and all with great economy in construction. The boiler can either be shipped as a whole or in sections, as may be required. The front water-leg with 95 its drum, the rear water-leg with its drum, the superheater steam-drum, the water-tubes, equalizer-tubes, and superheater-tubes may all be transported separately and the tubes expanded into the water-legs and drums at the 100 place of installation. The brickwork of the 105 boiler is also less than is ordinarily required, as the water-legs and drums make up the entire front and rear walls at and above the boiler.

It will be of course understood without detailed description that the usual boiler accessories are provided, such as safety-valve, steam-gage, water-level gage, blow-off pipes, and feed-inlet pipe, damper, &c.

In connection with the damper I might add 110 that with my construction the damper-frame and damper can be placed lower than in the longitudinal steam-drum constructions, for the reason that I can omit certain of the tubes *V* running to the rear drum, and thus leave a 115 space in which to swing the damper in the smoke-inlet with the damper-frame considerably lower than in most older constructions.

Having thus described my invention, what I claim as new, and desire to secure by Letters 120 Patent, is—

1. In a water-tube boiler, a series of water-tubes, water-leg therefor, and water-leg drum, with passage between the leg and drum, and stay-plates secured across the passage-way, 125

the stay-plates being bent to present their edges across the opening.

2. In a water-tube boiler, a series of water-tubes, and water-legs therefor, with water-leg drums running parallel to the water-legs, and stay-plates riveted to the drum across the opening between drum and water-leg, the stay-plates being bent to present their edges across the opening.

10 3. In a water-tube boiler, the combination with a series of water-tubes, of water-legs and water-leg drums therefor, equalizer-tubes between the water-leg drums, and an intermediate steam-drum—with steam-tubes connecting the intermediate drum with the water-leg drums.

4. In a water-tube boiler, the combination with a series of water-tubes, of water-legs and water-leg drums therefor, equalizer-tubes between the water-leg drums, an intermediate drum located above the plane of the water-leg drums, with tubes connecting the intermediate

drum with the water-leg drums above the water-line.

5. In a water-tube boiler, a water-leg with 25 a water-leg drum formed in a piece with the water-leg plates, with seams at the top of the drum and bottom of the water-leg, whereby no seam will be exposed to the hot gases.

6. In a water-tube boiler, the combination 30 with a series of water-tubes, water-legs at front and rear into which the water-tubes are expanded, drums at right angles to the water-tubes, into which the water-legs open throughout their length, and to which the water-legs 35 are riveted, equalizer-tubes connecting said drums, and an intermediate centrally-located drum, parallel to and in a plane above said water-leg drums, with tubes connecting the central drum with the water-leg drums.
